US00D990347S

(12) **United States Design Patent** (10) **Patent No.:** **US D990,347 S**
(45) **Date of Patent:** **** Jun. 27, 2023**

(54) **ANTI THEFT ALARM**

(71) Applicants: **Xijian Li**, Yueyang (CN); **Yugang Ke**, Guangzhou (CN)

(72) Inventors: **Xijian Li**, Yueyang (CN); **Yugang Ke**, Guangzhou (CN)

(73) Assignees: **Xijian Li**, Yueyang (CN); **Yugang Ke**, Guangzhou (CN)

(**) Term: **15 Years**

(21) Appl. No.: **29/847,531**

(22) Filed: **Jul. 26, 2022**

(51) LOC (14) Cl. **10-05**

(52) U.S. Cl.

USPC **D10/106.9**

(57) **CLAIM**

The ornamental design for an anti theft alarm, as shown and described.

DESCRIPTION

FIG. 1 is a front perspective view of an anti theft alarm, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the anti theft alarm, which form no part of the claimed design.

1 Claim, 7 Drawing Sheets
